N. S. FROST

BRUSH

Filed Dec. 23, 1921

Inventor
NELS S. FROST

By Attorney
Richard J. Cook

UNITED STATES PATENT OFFICE.

NELS S. FROST, OF SEATTLE, WASHINGTON.

BRUSH.

Application filed December 23, 1921. Serial No. 524,432.

To all whom it may concern:

Be it known that I, NELS S. FROST, a citizen of the United States, and a resident of the city of Seattle, county of King, State of Washington, have invented certain new and useful Improvements in Brushes, of which the following is a specification.

This invention relates to improvements in hair brushes, or the like, and has for its principal object to provide a brush of that character equipped with means whereby its bristles may be folded against the back portion of the brush in such manner as to permit the device to be disposed compactly within a case, or within the pocket, and whereby, when it is desired to use the brush, the bristles may be extended and locked in functional position.

Another object of the invention resides in the construction of a brush having a series of bristle holding bars pivotally mounted within the frame portion thereof and provided with means whereby they are connected with a plate that is shiftable to effect rotation of the bristle holding bars which will cause the bristles to be moved from folded to functional position, or vice versa.

Another object of the invention resides in the means for locking the shifting plate against movement to retain the bristles in extended position.

Still further objects of the invention reside in the arrangement of the bristle mounting bars and in the method of mounting the bristles therein, whereby the bunches, or packs, of bristles of successively arranged bars are disposed in offset, or staggered, relation to provide a more compact arrangement when they are in folded position.

In accomplishing these objects, I have provided the improved details of construction, the preferred forms of which are illustrated in the accompanying drawings, wherein—

Figure 1 is a top view of a brush, constructed according to the present invention, a part of the back portion being broken away to illustrate the manner of mounting the bristle holding members and the disposition of their actuating plate.

Figure 2 is a longitudinal section of the brush, taken on the line 2—2 in Figure 1, particularly illustrating the disposition of the shiftable plate and the manner in which

it is constructed for actuating the bristle holding bars.

Figure 3 is a transverse, sectional view, taken on the line 3—3 in Figure 2, illustrating the pivotal mounting of a bristle holding bar within the frame of the brush.

Figure 4 is a transverse, sectional view taken on the line 4—4 in Figure 1, particularly illustrating the means whereby the shiftable plate may be locked in position whereby it retains the bristles extended.

Figure 5 is a detail, perspective view of one of the bristle holding bars.

Figure 6 is a fragmental, sectional view showing the bristles in folded position.

Figure 7 is a top view of a brush having a part of the back plate broken away for better illustrating a shifting plate of an alternative construction.

Figure 8 is a sectional view taken on the line 8—8 in Figure 7.

Referring more in detail to the drawings—

1 designates, as a whole, what I term the frame or body of the brush. This comprises a base end portion 2 from which extend two opposite side rails 3 and 3', connected at their outer ends by means of a cross rail 4. A back, cover plate 5 is fixed between the rails by means of screws 6, as shown in Figure 1, and this is removable in order to facilitate the assembling of the bristle holding bars within the device or their removal therefrom.

Extending transversely between the frame rails is a plurality of regularly spaced apart bristle holding bars 7, each of which is provided with a series of apertures 8 wherein packs of bristles 9 are drawn, and provided at their opposite ends with trunnions 10 which seat pivotally within upwardly opening sockets 11 provided at oppositely disposed points of the rails 3 and 3'.

These bars 7 are all assembled within the body of the brush before the back plate is fixed in position, and then after the plate is fixed, the bars can not be displaced.

Disposed between the back plate of the brush and the bristle holding bars 7, is a plate 12. This extends longitudinally with respect to the brush body and is longitudinally slidable. It is provided, at the end which is adjacent the base of the brush, with a downturned flange 13 whereby it may be shifted, and formed therein in spaced

relation in accordance with the spacing of the bristle holding bars, are two rows of apertures; the apertures 14 of one row being offset slightly from the apertures 15 of the other, and all are so arranged as to receive therein teeth 16 and 17 which are formed centrally on the bristle holding bars. The teeth 16 and 17 extend at an angle of approximately 90 degrees with each other, and 10 are so located with respect to the apertures in the plate 12 that they act after the fashion of gear teeth meshing with a rack, so that when the plate 12 is shifted longitudinally in opposite directions, it causes a rotatable 15 movement of the bristle holding bars which, in turn, effects the simultaneous movement of the bristles to extended, functional position, as shown in Figure 2, or folded relation against the body of the brush, as shown 20 in Figure 6.

When the bars 7 have been rotated by an outward shifting of the plate 12 so that their bristles are positioned in an extended position, the shifting plate may then be 25 locked so as to prevent folding of the bristles while the brush is being used. The means which I have provided for locking the plate comprises a latch 18 which is slidably mounted within a transversely directed 30 slot 19 in the base portion 2 of the frame, and which has a lug 20 on its under side which is movable within a transverse slot 21 in that end of the plate 12. This latter slot is provided with an enlargement, or 35 lateral recess 22, at one end as is shown in dotted lines in Figure 1. When the latch is in position to lock the plate, the lug 20 thereon is seated within that end of the slot 21 that is opposite the recess 22, but when 40 it is shifted to the opposite side in alignment with the recess, it frees the plate so that the latter may be moved inwardly. Inward movement of the plate acting against the teeth of the bars 7 effects rotation of the bars 45 and thereby moves all of the bristles into a folded relation against the body of the brush so that the latter may then be conveniently placed within a case provided for it, or carried easily within the pocket.

50 It will be noted that I have arranged the packs of bristles of successive bars in offset relation to each other, so that when they are folded against the brush, they will nest with each other and thereby provide a more com-

pact arrangement than otherwise possible. 55 In mounting the bristles within the supporting bars, the desired number for each pack are drawn into the apertures of the bars and then, by means of a suitable clamp or tool, the lower end of the apertures are 60 pinched together so that the bristles can not be withdrawn. Should the bristles become worn off by long use, or should they become damaged, it is apparent that, by removing the back plate from the brush, the 65 bars may be removed and other bars, fitted with new bristles, may be inserted.

In Figures 7 and 8 I have illustrated a brush utilizing a shifting plate of an alternative type of construction and wherein the 70 bristle supporting bars are provided, at their opposite end, with the teeth 16 and 17 whereby they may be rotated, and, in place of the straight plate 12, I have provided a plate having extensions 25 and 26 which 75 overlie the ends of the bars and are provided with notches 27 and 28 for receiving these teeth, in such manner that actuation of the plate will effect rotation of the bars 80 7 similarly as does the plate disclosed in 80 the preferred construction of Figure 1.

I claim—

A brush of the character described comprising a base plate having spaced apart rails extending therefrom; said rails being 85 provided at points transversely opposite each other with upwardly opening sockets, bars extended between the frame rails having trunnions at their ends revoluble in said sockets, a plurality of packs of bristles 90 mounted in each set of said bars with the packs of successive bars arranged in offset relation with respect to each other, a shiftable plate mounted within the frame overlying said bars, a cover plate secured to the frame to retain the bars and shiftable plate in functional position, said shiftable plate having means whereby it is connected with all of said bars whereby shifting thereof 95 will effect rotation of the bars to cause the bristles to be folded against the brush body, or moved to extended position, and means for locking the plate against shiftable movement.

Signed at Seattle, Washington, this 16th 105 day of December, 1921.

NELS S. FROST.
